No 208

S. D. Ross - FOUNTAIN STOVE.

Patented Dec 19 1848

Dec. 208

Samuel D Rose Albany New York

Letter's Patent No. 208 Dated Dec 19, 1848 Validated June 19, 1848

The schedule referred to in this letter's patent and
making part of the same.

To whom it may concern. Doth know that I, Samuel D Rose of the City of Albany and State of New York, have produced a new ornamental design for a Parlor Stove which I call the Rosenthal Stove, and I do declare that the annexed and accompanying drawing is a full & accurate delineation of a stove constructed after my design, the sides and back not showing being similar to & symmetrical with the sides and front represented except that the back has the usual opening and flange for the applying & fitting of the pipe or smoke flue to stove.

What I claim as my invention and desire to have by letters patent is the combination and arrangement of ornamental figures and forms represented in the accompanying drawing making an ornamental design for a Parlor Stove.
